(57) **CLAIM**

The ornamental design for a rotor lamination for a generator, as shown and described.

DESCRIPTION

FIG. 1 is a perspective view of a rotor lamination for a generator.

FIG. 2 is a top plan view of the rotor lamination for a generator.

FIG. 3 is a bottom plan view of the rotor lamination for a generator.

FIG. 4 is a front elevation view of the rotor lamination for a generator.

FIG. 5 is a back elevation view of the rotor lamination for a generator.

FIG. 6 is a left side elevation view of the rotor lamination for a generator.

FIG. 7 is a right side elevation view of the rotor lamination for a generator; and,

FIG. 8 is a top plan view of the rotor lamination for a generator shown in environmental use.

The broken lines shown depict the portions of the rotor lamination for a generator that form no part of the claimed design.
